DESIGN FOR A COMBINATION TOOL

William F. McDowell, Pueblo, Colo.

Application May 17, 1946, Serial No. 129,814

Term of patent 14 years

(Cl. D93—4)

To all whom it may concern:

Be it known that I, William F. McDowell, a citizen of the United States of America, residing at Pueblo, county of Pueblo, and State of Colorado, have invented a new, original, and ornamental Design for a Combination Tool, of which the following is a specification, reference being had to the accompanying drawing, forming a part thereof, wherein:

Figure 1 is a side view of a combination tool, showing my new design;

Figure 2 is a view of one edge of the tool;

Figure 3 is a view of the opposite edge of the tool;

Figure 4 is a top plan view;

Figure 5 is a section taken on line 5—5 of Figure 1;

Figure 6 is a section taken on line 6—6 of Figure 1.

I claim:

The ornamental design for a combination tool, as shown.

WM. F. McDOWELL.
